UNITED STATES PATENT OFFICE

WILLIAM E. LEIBING, OF OAKLAND, CALIFORNIA

CARBURETOR

Application filed June 4, 1923. Serial No. 643,150.

This invention relates to carburetors generally. The particular objects of the invention are to improve the carburetion of hydrocarbons for the operation of internal combustion motors, and by so doing reducing the fuel consumption and maintaining a higher efficiency in the operation of motors than that obtained in proportion to the fuel used by devices of this type as generally employed at the present time. Other objects are to provide a carburetor wherein the velocity through the Venturi tube controls through a valve the fuel volume admitted into the vaporizing chamber; to provide a carburetor wherein the fuel nozzle associated with the Venturi tube is of conical formation and has a peripheral outlet below its upper end, and to provide a Venturi tube operably movable in axial alignment with the fuel nozzle and controlling the operation of the carburetor. Other objects are to provide a Venturi tube the minimum diameter of which approximates the maximum diameter of the fuel nozzle and the mounting of one member relatively movable to the other enabling the velocity of air between the two to be regulated in accordance with their relative position, and to provide a low speed nozzle from which fuel is discharged in a direction diametrically opposite to the direction of passage of the air employed for vaporizing a fuel issuing from said nozzle.

With the above mentioned and other objects in view, the invention consists in the novel construction and combination of parts hereinafter described, illustrated in the accompanying drawings, and set forth in the claims hereto appended, it being understood that various changes in the form, proportion, size and minor details of construction within the scope of the claims may be resorted to without departing from the spirit or sacrificing any of the advantages of the invention.

To more fully comprehend the invention reference is directed to the accompanying drawings, wherein—

Fig. 1 is a vertical sectional view of the preferred embodiment of my invention.

Fig. 2 is a transverse sectional view taken on the line 2—2 of Fig. 1.

Fig. 3 is a cross sectional view taken on the line 3—3 of Fig. 2.

Fig. 4 is a sectional view of the metering valve elevator and chamber taken on the line 4—4 of Fig. 3.

Fig. 5 is a sectional view on the line 5—5 of Fig. 3 illustrating the low speed well and the primary high speed well.

Fig. 6 is a view in broken side elevation of the upper portion of the Venturi tube and.

Fig. 7 is a view in elevation of the conical secondary high speed fuel nozzle.

Referring to the drawings wherein like characters of reference designate corresponding parts throughout the several views, 1 indicates generally, the whole casting forming a carburetor and which casting is provided with a float chamber 2 having the conventional inlet fuel supply port 3 controlled by the needle valve 4 associated with the float 5. This construction is well known and forms no part of the present invention. From the float chamber extends an outlet 6 branching laterally as at 7 and 8, said branches connected respectively with the chambers 9 and 10, the bases of which are closed by the respective plugs 11. Vertically from these chambers extend the respective low speed fuel nozzle 12 and the primary high speed fuel nozzle 13, the nozzle 12 terminating slightly above the contracted portion of the low speed air inlet 15 which surrounds the free end of said nozzle. The admittance of air into the inlet 15 is controlled by the adjustment of screw 16 adapted to project thereinto and whose rotation is regulated by the lock nut 17. The primary high speed nozzle 13 extends axially into a vertical primary high speed air inlet 18 and is provided with lateral ports 18'. In both of these constructions it will be observed that the air entering inlets 15 and 18 travels in a path directly opposite to the flow of fuel in the respective nozzles and in the matter of the low speed nozzle the air travels in a direction diametrically opposite to the direction of discharge of the fuel from the nozzle.

In the casting 1 the inlets 15 and 18 terminate respectively into chambers 19 and 20, 100

the chamber 20 communicating with a vertical channel 21 and the chamber 19 communicating through a port 22 with the interior of a metering valve elevator well 23 connected to and in vertical alignment with the channel 21. At its lower end the channel 21 is formed with an enlarged chamber 23' in which reciprocates the conical primary mixture metering valve 24, the upward movement of which is adapted to reduce the passage of primary mixture from the channel 21 to the lateral channel 25 connecting with the high speed secondary mixture nozzle hereinafter described. Upwardly from the valve 24 extends a stem 26 carrying on its upper end a metering valve elevator 27 slidably mounted within the well 23. The well 23 is formed within a suitable bushing 28 having a base closed as indicated at 28' and formed with the port 22 and the interior of the well on opposite sides is provided with vertically disposed recesses 29 increasing in depth toward the upper end of the well and said recesses connect through port 30 in the bushing 28 with a pipe 31 which in turn connects as at 32 with the outlet of the carburetor at a point beyond the secondary high speed mixture nozzle and the Venturi tube associated therewith which I will hereinafter describe. It will be observed that the main supply of fuel mixture for operating the motor under low speed or idling conditions is admitted directly through the port 22 and passes through the recesses 29 into the carburetor at the point 32 through pipe 31, the metering valve elevator being held in partial raised position by suction to open recesses 29 for this passage of fuel. This fuel mixture supply being extremely limited and only sufficient to maintain the idling operation of the motor is adapted to enter the well 23 under substantially all conditions of operation, but it will be observed that the main mixture supply for the operation of the motor under other conditions does not enter the well 23 but passes through channel 25. Channel 25 which is illustrated as being horizontally disposed, is provided with a vertical branch 33 which is disposed centrally of the lower end of the vertically disposed main chamber 34, the lower end of which is open, providing a secondary air inlet 35. The branch 33 mounts a high speed secondary mixture nozzle 36 threaded at its lower end thereinto, and said nozzle is of substantially conical shape and is constructed of a base 37 drilled as at 38 with a plurality of passages extending inwardly and downwardly towards its central channel 39, and which base is provided with an upwardly projecting central stud 40 at its base surrounded by a downwardly and inwardly inclined wall 41. Secured to the stud 40 is a conical tip 42, the base of which is of a diameter to correspond with the diameter of the base at the periphery of the face 41, and said tip has a bottom wall disposed at an incline corresponding to the face 41 of the base 37. This nozzle construction provides a conical nozzle 70 formed with a peripheral discharge orifice 44 circumferentially disposed about the nozzle at a point below its upper end. Mounted for reciprocation within the main chamber 34 is a tubular casting 45, the passage in which is of the conventional Venturi tube formation 46, as in the drawing, the lower end of the tube axially receiving the high speed secondary mixture nozzle. The diameter and formation of the Venturi tube 75 at its lower end is such that the tube during its vertical adjustment causes a variation in volume and velocity of the secondary air admitted to pass upwardly through said tube. The upper end of the tube registers with the normal mixture outlet 47 of the carburetor and is guided by the annular flange 48. During the operating of the carburetor, the tube is manually raised and lowered by an operator who imparts axial rotation to the rod 49 mounting the operating forks 50 connected through fulcrum points 51 with the outer surface of the Venturi tube. The outer surface of this tube mounts a standard 52 to which is pivotally connected one end of a compensating arm 53, the free end of which overlies the elevator 27 and affords a stop for the upward movement of the elevator in accordance with the vertical adjustment of the Venturi tube, the terminal end of said arm engaging a guide pin 54 extending vertically from the elevator 27. The upper end of the guide pin 54 carries a removable bearing button 54' for engagement with said compensating arm. An adjustable fulcrum 55 of the knife blade type is carried on the end of each bifurcation of the body 56 and overlies a portion of the compensating arm varying the stroke thereof in accordance with the adjustment of the fulcrum longitudinally of the bifurcations. The adjustment of this fulcrum is obtained by the inward or outward threading of the screw member 57, the head of which cooperates with an annular groove 58 at the outer end of the body 56. An annular flange 59 disposed radially of the body of the member 45 contacts with a shoulder 60 on the wall of the main chamber 34 and affords a stop for limiting the downward movement of the venturi in the chamber. To relieve the pressure in the space between said flange and stop and to permit the free vertical sliding movement of the Venturi tube I provide a tubular connection 61 leading to the main outlet of the carburetor. The lower enlarged chamber 23' of the channel 21 is provided with a vent and seepage outlet 63 as illustrated in Figs. 1 and 3 below the metering valve 24. 80 85 90 95 100 105 110 115 120 125 130

The carburetor being assembled as in the drawings and the same connected to the fuel supply at the point 3 and with the motor intake manifold at the end of its main mixing tube, the same operates in the following manner.

After the motor has been started the low speed fuel mixture nozzle supplies the necessary fuel which mixes with the air admitted into port 15 for operating the motor under low speed conditions, this mixture entering the motor through the pipe 31 and port 32. In the operation of the motor under low speed conditions it is to be understood that the Venturi tube 45 is positioned at its lower limit of movement to cut off the air supply through the air inlet 35 by the manual operation of said tube. This position of the parts permits the suction of the engine to exert its full force through the tube 31 on the metering valve elevator 27 which will elevate said valve to such a position that the required quantity of atomized fuel from the low speed nozzle 12 will be drawn past the metering valve elevator which in this operation acts as a valve in governing the passage of fuel through the recesses 29 into the pipe 31 and to the engine. The increased speed of the motor occasioned by the operator manipulating the throttle lever to elevate the Venturi tube 45 gradually increases the space between the wall of the Venturi tube and the surface of the nozzle 37 reducing the velocity of the air between these two surfaces, thus admitting a gradually increasing volume of mixture dependent on the height of elevation of the Venturi tube. The greater the Venturi tube 45 is elevated the lower down the terminal end of the lever 53 is forced, as this lever operates in a reverse direction to the movement of the Venturi tube, consequently the higher the Venturi tube is elevated the lower the stop 53 is moved for limiting the closing movement of the metering valve 24. On the lowering of the Venturi tube by the operation of the throttle the velocity of the air between the surface of the Venturi tube and the nozzle 37 is gradually increased causing a greater tendency for fuel mixture flow from the annular discharge port 44, and to compensate for this and maintain the proper proportion of fuel mixture, the free end of the stop arm 53 raises in proportion to the lowering of the Venturi tube permitting the suction at the end of pipe 31 to cause a gradual shut-off of the fuel mixture flow around valve 24. It will be observed that under all operating conditions the suction of the motor acting on the metering valve elevator 27 causes an operation of the valve 24 in accordance with the degree of suction, and that the height of this elevator is limited by the free end of the arm 53 which is directly con-

trolled by the position of the Venturi tube 45.

The foregoing described operations are based on the normal operation of the motor, as for instance when the vehicle is traversing a level road, but when an abnormal condition arises such for instance as where the vehicle is called to climb a hill, and a heavier load is thereby placed onto the motor thereof, the elevator above described does not work at such time under mechanical control, but its action is directly controlled by the vacuum, which in turn is controlled by the revolution of the engine, and the position of the venturi.

The action of the above mentioned elevator is as follows:—The varying cross sections of slots 29 is such that the engine suction is just sufficient to maintain the weight of the elevator in contact with mechanical arm 53 during the normal operation of the motor. Inasmuch as this cross section is just sufficient to maintain the weight of the elevator in such contact, any decrease of vacuum must necessarily allow said elevator to fall in direct proportion as such controlling vacuum falls. It is obvious that the moment such abnormal condition ceases to exist, as for instance when the vehicle has topped a hill, the vacuum immediately builds up due to the increase in engine revolutions and the elevator goes back to its former mechanically controlled position.

Under these conditions, it is apparent that a vehicle can be run with the leanest possible mixture for all level work with no sacrifice of motor performance when grades or hills are encountered.

Inasmuch as there is associated interiorly with the Venturi tube, a fixed secondary mixture nozzle the outer wall surface of which contacts with the inner wall surface of the Venturi tube to provide an annular passage therebetween formed on substantially proper stream lines, and inasmuch as the Venturi tube is a vertically movable one with respect to the said nozzle, it is apparent that the throat of the venturi, and which constitutes the smallest cross sectional area of the annular passage way, is a variable one, the variation of the throat being produced by the vertical movement permitted the Venturi tube 45, this variable throat construction being designed to take the place of the customary throttle employed in connection with Venturi tubes with the consequent result that at partially closed throttle the impact of air across the annular passage comprising the gasoline jet is greater than at wide open throttle, and it is obvious that the relation of these associated parts of the venturi is such as to provide for both mechanical and automatic control thereof.

While the invention has been described in its preferred embodiment relative to struc-

tural features, I do not wish to be understood as limiting or restricting the invention to the details of construction herein shown and described, but wish to claim as broadly as the state of the art will permit, the combination in a carburetor of a vertically movable Venturi tube having associated interiorly therewith a fixed or stationary main fuel mixture nozzle, the cross section of the throat 10 of the Venturi tube being variable in accordance with the vertical movement imparted to said movable member relative to the fixed fuel mixture nozzle, and which nozzle co-operates with the movable Venturi tube 15 to provide a variable annular passage on proper stream lines.

Having thus described my invention, what I claim as new and desire to protect by Letters Patent of the United States is:—

20 1. A carburetor including a main mixing chamber, means for controlling the mixture velocity therethrough, means for feeding fuel mixture to said mixing chamber, a valve actuated by the vacuum at the upper end of said 25 mixing chamber to reduce the fuel mixture feed to the mixing chamber, and a mechanically operated stop for engaging and limiting the closing movement of the valve, said stop being operated by said means for controlling the mixture velocity.

2. A carburetor including a main mixing chamber; a Venturi tube therein mounted for mechanical vertical reciprocation, a nozzle at the base of the chamber and extending into 35 the end of the Venturi tube, a valve actuated by the vacuum in said mixing chamber to reduce the fuel mixture fed to the nozzle, and means operated by the movement of the Venturi tube for limiting the closing of said 40 valve dependent upon the position of said Venturi tube.

3. A carburetor comprising a fuel chamber, a mixing chamber, a pair of passages in the carburetor between said fuel chamber 45 and mixing chamber, independent air inlets to said passages, nozzles in said air inlets for atomizing fuel flowing therefrom through said passages to the mixing chamber, a secondary nozzle in said mixing chamber having one of said passages communicating therewith, and suction operated means controlling the flow of fuel mixture to said mixing chamber.

4. A carburetor, comprising a mixing 55 chamber having an air inlet at one end and a mixture outlet at the opposite end, a pair of fuel mixture supply passages formed in the carburetor communicating with the mixing chamber adjacent the inlet and outlet 60 ends respectively, manually operated means in the mixing chamber controlling the outlet of one of the passages thereto, and suction operated means controlling mixture in both of said passages proportionately to the suction in the mixing chamber and in advance

of entry of the mixture into the mixing chamber.

5. A carburetor, comprising a mixing chamber having an air inlet at one end and a mixture outlet at the opposite end, a pair of fuel mixture supply passages formed in the carburetor communicating with the mixing chamber adjacent the inlet and outlet ends respectively, manually operated means in the mixing chamber controlling the outlet of one of the passages thereto, and suction operated means controlling mixture in both of said passages proportionately to the suction in the mixing chamber, and means operated by said manually operated means for limiting the operation of the suction operated means in a predetermined manner and in advance of entry of the mixture into the mixing chamber.

6. A carburetor, comprising a mixing chamber having an air inlet at one end and a mixture outlet at the opposite end, a pair of fuel mixture supply passages formed in the carburetor communicating with the mixing chamber adjacent the inlet and outlet ends respectively, manually operated means in the mixing chamber controlling the outlet of one of the passages thereto, and suction operated means controlling fluid flow in both of said passages proportionately to the suction in the mixing chamber, means operated by the manually operated means for limiting the operation of the suction operated means proportionately to the operation of said manual means, and means for adjusting the last mentioned means to vary the proportionate control between the manual and suction operated means.

7. A carburetor, comprising a mixing chamber having an air inlet at one end and a mixture outlet at the other end, a secondary fuel mixture nozzle mounted in axial relation in said mixing chamber, a pair of fuel mixture passages formed in said carburetor, one of said passages communicating with said secondary fuel mixture nozzle and the other of said passages communicating with said mixing chamber at the mixture outlet end, air inlets communicating with each of said fuel mixture passages, fuel nozzles in said inlets, suction operated means controlling each of said passages, manually operated means in said mixing chamber controlling the air inlet and secondary fuel mixture nozzle therein and means associated with said manually operated means and said suction means controlling the operation of said suction operated means in a predetermined manner.

8. A carburetor, comprising a mixing chamber, a pair of fuel mixture supply passages formed in the carburetor communicating with the mixing chamber, suction operated interconnected valves for metering the flow in said passages in inverse proportion

respectively and means for adjusting the proportionate operation of said valves.

9. A carburetor, comprising a mixing chamber, a pair of fuel mixture supply passages formed in the carburetor communicating with the mixing chamber at one end, atomizing means at the opposite ends in said passages remote from said mixing chamber, and suction operated valving means controlling the flow in said passages in inverse proportion respectively.

10. A carburetor, comprising a mixing chamber, a pair of fuel mixture supply passages formed in the carburetor communicating with said mixing chamber, atomizing means in said passages, and a suction operated metering means controlling mixture flow in both passages between said atomizing means and said mixing chamber and in advance of communication of said passages with the mixing chamber.

11. A carburetor, comprising a mixing chamber, a pair of fuel mixture supply passages formed in the carburetor communicating with said mixing chamber, said passages having axially aligned portions, a pair of suction operated interconnected valve members slidably mounted in said aligned portions of said passages, and a conduit extending between said mixing chamber and said aligned portions of said passages whereby said valve members are operated by the suction through said conduit.

12. A carburetor comprising a mixing chamber, a well and an aligned channel formed in said carburetor, a pair of fuel mixture passages formed in the carburetor effecting communication between the mixing chamber and the well and aligned channel respectively, suction operated valve members slidably mounted in said well and aligned channel separately controlling said pair of passages, one of said pair of passages forming a suction passage in the carburetor between said mixing chamber and said well to permit operation of said valve members by suction, and manually operated means for controlling the operation of said valve members by the suction.

13. A carburetor, comprising a mixing chamber, a well formed in said carburetor, a vertical channel formed in alignment with said well, a pair of fuel mixture passages formed in the carburetor effecting communication between said well and vertical channel respectively, and said mixing chamber, suction-operated valve members slidably mounted in said well and vertical channel separately controlling said pair of passages, one of said passages forming a suction passage between said mixing chamber and said well for transmitting suction to operate said valve members to independently control fuel mixture flow in said passages, manually operated means in said mixing chamber for controlling

the flow therethrough, and means operable by the last-mentioned means and adjustable relative thereto for controlling the operation of said valve members by suction.

14. A carburetor, comprising a mixing chamber, a well formed and an aligned channel formed in said carburetor, a pair of fuel mixture passages formed in the carburetor providing communication between said well and channel respectively, and said mixing chamber, suction-operated valve members slidably mounted in said well and aligned channel separately controlling said pair of passages, one of said passages forming a suction passage in the carburetor between said mixing chamber and said well for transmitting suction to operate said valve members, manually operated means in said mixing chamber for controlling the flow therethrough, a lever operable by the last-mentioned means for controlling the operation of said valve members by suction, and means for adjusting the operation of said lever for changing the relative control of said valve members by said manually operated means.

15. A carburetor, comprising a mixing chamber, a pair of fuel mixture supply passages communicating with said mixing chamber, valve means controlling the supply of fuel mixture through said passages, manually operated means for controlling the flow through said mixing chamber, a lever operated by the manually operated means controlling the operation of said valve means, and an adjustable fulcrum for said lever for varying the operative relation between said manually operated means and said valve means.

In testimony whereof I have signed my name to this specification.

WILLIAM E. LEIBING.
